UNITED STATES PATENT OFFICE

2,447,431

SHIRT COLLAR

Melville F. Rogers, Ottawa, Ontario, Canada

Application December 17, 1946, Serial No. 716,777

3 Claims. (Cl. 2—137)

1

This invention relates to a shirt collar.

The main object of the invention is to provide a collar for a shirt, which will hold a tie when knotted, up in its proper or intended position.

Another object of the invention is to provide such a collar at a cost not substantially greater, if at all greater, than that of the usual collar.

It is well known that the tie, after it has been knotted and adjusted in its required position, usually drops at the front of the collar. The collar of the present invention is such that the tie remains in its intended position, the knot being effectively held up at the centre of the collar.

In the drawing, the preferred form of a collar made according to the invention, has been shown, the collar shown being of the stiff kind. While experiments with a stiff collar only have been made so far, it is believed that the invention is applicable to a semi-soft collar as well, and the invention may also be applicable to an attached collar.

In the drawing,

Figure 1 is a fragmentary front elevation of a detached, stiff collar made according to the invention; and

Figure 2 is a front view of the collar, with the front fold removed, and showing a tie, partly in solid lines and partly in phantom, in operative position.

Referring now by numerals to the drawing, 10 is a detached, stiff collar of which 11 is the outer fold and 12 the inner fold. From one end of the inner fold extends a fastening tab or tongue 13 having a buttonhole 14. The collar so far described, including the tongue 13, is of conventional form or make.

From the opposite end of the inner fold 12 extends another tab or tongue 15 which likewise has a buttonhole adapted to register with the buttonhole of the tongue 13 to fasten the front of the collar to the stud (not shown) used through the shirt collar band (not shown) in the usual manner.

The tongue 15, instead of being of conventional form or shape, such as the other tongue 13, has its upper edge formed with a notch or recess 16, preferably defining a more or less semi-circular edge. Preferably, the tongue 15 is slightly longer than the other tongue.

The tongue 15 is adapted to be fastened to the button outwardly of the tongue 13. That is, the

2

tongue 13 is first fastened to the collar button and the tongue 15 is fastened to the button to overlie or overlap the tongue 13.

The tie, T, is applied and knotted in the usual manner, with both tongues fastened to the button in the usual manner, following which the tab 15 is inserted between the folds 11 and 12 so that its free or outer end overlies the tie at or near the front of the collar, as best shown in Figure 2, the tie passing lengthwise through the slot or recess 16. The tie will thus be held in its proper position, or will not appreciably drop at the front of the collar.

What I claim is:

15 1. A shirt collar having outer and inner folds and fastening tongues extending from opposite ends of said inner fold adapted to overlap one another at the front of the collar, one of said tongues being of a length such as to extend between said folds and to engage at its outer end the juncture portion of said folds, said one of said tongues having its upper portion cut out defining an elongated recess through which the tie is received lengthwise and presenting an upper edge below the knot of the tie by which the knot is supported when said tongues are attached to the stud.

2. In a shirt collar as set forth in claim 1, said recess taking the form of a shallow U.

3. A shirt collar having outer and inner folds and fastening tongues extending from opposite ends of said inner fold adapted to overlap one another at the front of the collar, one of said tongues being of a length such as to extend between said folds, said one of said tongues having its upper portion in part cut out to define a shallow elongated recess in part extending under one of said folds adapted to receive the tie lengthwise and presenting an upper edge forming a support for the knot of the tie when said tongues are attached to the stud.

35 4. A shirt collar having outer and inner folds and fastening tongues extending from opposite ends of said inner fold adapted to overlap one another at the front of the collar, one of said tongues being of a length such as to extend between said folds, said one of said tongues having its upper portion in part cut out to define a shallow elongated recess in part extending under one of said folds adapted to receive the tie lengthwise and presenting an upper edge forming a support for the knot of the tie when said tongues are attached to the stud.
